H. E. BARTSCH

DRAFT ARM

Filed Jan. 7, 1924

UNITED STATES PATENT OFFICE.

HERBERT E. BARTSCH, OF CHICAGO, ILLINOIS, ASSIGNOR TO UNIVERSAL DRAFT GEAR ATTACHMENT COMPANY, A CORPORATION OF ILLINOIS.

DRAFT ARM.

Application filed January 7, 1924. Serial No. 684,793.

To all whom it may concern:

- Be it known that I, HERBERT E. BARTSCH, a citizen of the United States, and resident of Chicago, county of Cook, and State of Illinois, have invented certain new and useful Improvements in Draft Arms, of which the following is a specification, and which are illustrated in the accompanying drawings, forming a part thereof.
- 10 This invention relates to draft rigging and particularly to the connections between the supporting straps for the draw bar and draft gear and the side members of the draft arms, draft plates, etc. The principal object of the invention is to provide connections between these members that will be very easy to construct and assemble and yet will afford great strength and durability in service.
- 15 Further objects and advantages of the invention will become apparent as the disclosure proceeds and the description is read in connection with the accompanying drawings illustrating a selected embodiment of the invention, and in which—

- 20 Fig. 1 is a fragmentary sectional view of a draft arm illustrating a joint embodying the invention;
- 25 Fig. 2 is a fragmentary side elevation of the parts shown in Fig. 1;
- 30 Fig. 3 is a horizontal sectional view taken on the line 3—3 of Fig. 2, and
- 35 Fig. 4 is a perspective view of one of the supporting straps.

- 40 The invention is here illustrated in connection with a cast draft arm, a portion of the front end of which is illustrated at 10 (Fig. 2). It comprises two laterally spaced side members 11, 11, between which the draw bar 12, and the draft gear are supported on straps, one of which is illustrated at 13, extending transversely between the side members 11 and secured thereto. The side members are here illustrated as composed 45 of webs 14 having upper and lower marginal flanges 15 and 16 merging into an end flange 17. The flanges 16 are thickened adjacent to the end, as indicated at 18, and just above these thickened portions the webs are perforated, as indicated at 19, to receive the straps 13. The webs 14 are thickened around these perforations, as in-

dicated at 21, and the end flange 17 is thickened at 22 in front of the strap.

According to this invention the ends of the straps are interlocked with the side members of the draft arm so that the fastening means is relieved of all strain and there is no tendency in service to pry or wring the fastening means loose. In the present embodiment the thickened portions 18 of the flanges 16 are provided with depressions or pockets 24 which receive complementary studs or bosses 25 on the straps. The presence of the bosses, of course, makes it necessary to enlarge the perforations 19 and these additional spaces are filled with shims which lie on top of the strap and preferably extend through the webs 14. The shims prevent the strap from rising and thereby retain the studs or bosses 25 in the pockets 24 and effectually bind the parts together. It is only necessary then to secure the shims in place and the fastening is complete. This is conveniently accomplished by providing the necessary perforations and inserting pins 27 through the shims, the straps and the flanges and these pins may easily be secured by cotter keys 28.

From the foregoing it will be clear that this invention provides a joint between the supporting straps and the side members of the draft arm, draft plate and the like, that can be assembled easily and correctly by unskilled labor and at the same time it will be strong enough to withstand the strains of service and securely maintain the side members in their proper relation.

I claim as my invention:

1. A draft plate having at each side a web and a flange at the margin of the web, each flange being provided with a pocket and each web being perforated adjacent to the pocket in the flange, a supporting strap extending through said perforations and having portions seated in said pockets and means for securing the strap to the draft plate.

2. A draft plate having at each side a web and a flange at the margin of the web, each flange being provided with a pocket and each web being perforated adjacent to the pocket in the flange, a supporting strap extending through said perforations and

2
having portions seated in said pockets, shims lying on said strap and extending into the perforations in the webs and fastening device extending through the shims, the straps and the flanges.

3. A draft plate having at each side a web and a flange at the margin of the web, each flange being provided with a pocket

and each web being perforated adjacent to the pocket in the flange, a supporting strap 10 extending through said perforations and having lugs seated in said pockets, shims filling the perforations above the strap and means for securing the shims in place.

HERBERT E. BARTSCH.
